COLLAR STRETCHER

Abraham Goldstein, Brooklyn, N. Y.

Application January 4, 1955, Serial No. 479,767

6 Claims. (Cl. 223—52.1)

This invention generally relates to a collar stretcher and more specifically provides a device for stretching collars or similar garment portions that are desirable of being enlarged.

Although fabrics generally are treated to render them shrink-proof, this treatment is not always effective and shrinkage sometimes occurs from laundering a garment. Also, the size markings on such garments may be erroneous and it is frequently desirable to enlarge garment portions such as shirt collars regardless of the reason. Tight collars cause considerable discomfort to the wearer as well as being actually harmful to the health since circulation may be retarded by tight collars or the like. Accordingly, it is a primary object of the present invention to provide a collar stretcher for enlarging collars to a desired size without damage to the fabric or material from which the garment is constructed.

Another object of the present invention is to provide a collar stretcher which may be stressed and retained in a stressed or tensioned position so that the collar stretching operation may be carried out over a relatively long period of time.

Still another important object of the present invention is to provide a collar stretcher having a device for engaging over the front part of the collar thereby eliminating undue stress on the threads holding the collar button on during the stretching operation.

Other important objects of the present invention will reside in its simplicity of construction, ease of operation, its adaptation for its specific purpose and its relatively inexpensive manufacture.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a top plan view of the collar stretcher of the present invention;

Figure 2 is a transverse, vertical sectional view taken substantially upon a plane passing along section line 2—2 of Figure 1 showing the details of construction of the collar stretcher of the present invention;

Figure 3 is a side elevational view showing the collar stretcher of the present invention in position on a collar with the front portion of the shirt being engaged by the device for eliminating pressure on the collar button;

Figure 4 is a plan view with portions of the collar stretcher being broken away showing the details of construction and relationship of the various elements;

Figure 5 is a vertical, sectional view, taken substantially upon a plane passing along section line 5—5 of Figure 4 showing further structural details of the collar stretcher of the present invention and showing the utility thereof in conjunction with a clothes hanger; and

Figure 6 is an enlarged fragmentary view showing the brake construction for retaining the collar stretcher in tensioned position.

2

Referring now specifically to the drawings, it will be seen that the numeral 10 generally designates the collar stretcher of the present invention including a plurality of segmental members 12, 14, and 16, each of which is provided with an upstanding peripheral outer wall 18 which projects above and below a main body portion 20. Secured to and extending along the outer surface of the peripheral walls 18 of the members 12, 14 and 16 is a sponge rubber cushion member 22 for engaging the inner surface of a shirt collar 24. The body portion 20 of each of the segmental members is provided with an inwardly facing slot 26 having an inward projection 28, or lug, therein substantially at the mid-point thereof for a purpose described hereinafter.

Rotatably journaled within the segmental members 12, 14 and 16 is a tubular upstanding member 29 having a plurality of radial handles 30 adjacent the upper end thereof. The lower end of the tubular member 29 is integrally formed with a concentric plate-like member 32 having three cam surfaces 34, 36 and 38 integrally formed thereon for engaging in the slot 26 and contacting the projecting lugs 28 therein. The ends of each of the cam members 34, 36 and 38 are provided with a projecting lug 40 on the outer end thereof for limiting rotational movement of the plate 32 in relation to the segmental members 12, 14 and 16.

The adjacent edges of the segmental members 12, 14 and 16 are held in assembled relation by a plurality of pairs of coil springs 42 with the coil springs being disposed above and below the main body portions 20 of the segmental members 12, 14 and 16. It will be seen that the cam surfaces 34, 36, 38 are narrower in width than the slot 26 thereby permitting limited vertical movement of the plate 32 in relation to the segmental members 12, 14 and 16 for a purpose described hereinafter. It is also noted that the lugs 28 are substantially the same thickness as the cam members 34, 36 and 38 so that the cam members 38 may be vertically moved in the slots 26 for disengagement from the lugs 28 thereby permitting inward contracting movement of the segmental members 12, 14 and 16. A peripheral depending flange 44 is provided on the undersurface of the plate 32 and an upstanding flange 46 is provided on the upper surface thereof generally forming guides and limits for the inward movement of the segmental members 12, 14 and 16. Positioned in spaced relation to the plate 32 on the tubular member 29 is a cam 48 for engaging a circular ring 50 having a radially extending arm 52 integrally formed therewith. The ring 50 is provided with an inwardly extending detent 54 and the cam 48 is provided with a recess 56 for engagement with the detent 54 for a purpose described hereinafter. The radial arm 52 extends outwardly over the segmental member 14 and is attached thereto by a screw-threaded member 58 riding in a slot 60 which guides and limits the movement of the arm 52. The outer end of the arm 52 terminates in a downwardly extending portion 64 having rearwardly inclined wing portions 66 together with a slot 68 in the lower edge thereof for positioning over a collar button 70. It will be seen that the wing portions 66 are generally positioned in spaced relation to the apex of the segmental member 14 for receiving the closure portion of a collar 24 therebetween and forming wing presser plates. The matched detent 54 and recess 56 generally orientates the extending rod 52 in relation to the cam 48 so that the wing portions 66 will not be in close engagement with the segmental member 14 when the segmental members 12, 14 and 16 are contracted. It will be seen that the tubular member 29 permits the insertion of the coat hanger hook 72 thereby permitting use of the device with a coat hanger 74.

As illustrated in Figure 6, a friction brake 76 is mounted adjacent one of the lugs 28 and is embedded in

the segmental member 14 by a spring member 78 where-
in the cam 36 passing by the lug 28 will engage the
friction brake 76 so that the plate 32 will be locked in
position for expanding the segmental members 12, 14
and 16 until such time as the plate is raised vertically
thereby permitting contraction of the segmental members
12, 14 and 16.

In operation, the segmental members 12, 14 and 16
are normally positioned in contracted relation as illus-
trated in Figure 1 with the springs 42 resiliently urging
the segmental members together. In this position and
with the arm 52 moved outwardly as far as possible, the
collar stretcher 10 is inserted within the collar 24 and
the wing portions 66 positioned under the wing tips of
the collar 24 and over the collar button 70 for engaging
the closure portion of the collar 24. This contracted
relation is assured by raising the plate 32 upwardly there-
by assuring the cam members 34, 36 and 38 ride above
the projecting lugs 28 in the slots 26 so that the seg-
mental members 12, 14 and 16 are in their innermost
position. Of course, the plate 32 must be rotated so
that the smallest portion of the cam members 34, 36
and 38 will pass down over the face of the lugs 28. As
soon as the handles 30 are started to rotate, the recess
56 and detent 54 on the cam 48 and ring member 50,
respectively, are misaligned thereby securely clamping
the closure portion of the collar 24. As the cam mem-
bers 34, 36 and 38 move arcuately, they will engage the
lugs 28 and force the segmental members 12, 14 and 16
apart generally as indicated in Figure 4. The friction
brake 76 engages one of the cam surfaces and retains
it in its rotated position until such time as the entire
cam plate 32 is raised vertically thereby releasing the
cams from the lugs 28, thereby permitting the collar
stretcher 10 of the above invention to be utilized over
a long period of time under tension. Due to the par-
ticular curvature of the cam 48, it will be seen that
relative constant pressure is maintained on the wing por-
tions 66 thereby eliminating damage to the arm 52 and
assuring that too much pressure will not be exerted upon
the collar button 70.

From the foregoing, the construction and operation of
the device will be readily understood and further expla-
nation is believed to be unnecessary. However, since
numerous modifications and changes will readily occur
to those skilled in the art, it is not desired to limit the

invention to the exact construction shown and described,
and accordingly, all suitable modifications and equiva-
lents may be resorted to, falling within the scope of the
 appended claims.

5 What is claimed as new is as follows:

1. A substantially annular expandable and contractible
collar stretcher comprising a plurality of substantially ar-
cuate segments arranged end-to-end, tension spring con-
necting said segments together to move the same in-
wardly to contract said stretcher, and cams means for
10 moving said segments outwardly to expand the stretcher
comprising a rotary plate within the confines of said
segments, internal slots in said segments in which said
plate is rotatable, peripheral cams on said plate rotatable
15 in said slots by said plate, and means in said slots
engaged by said cams to cam said segments outwardly
in opposition to said springs.

2. The combination of claim 1, said means comprising
lugs in said slots.

3. The combination of claim 1, and a tubular rotary
member fixed on said plate for rotating the same and
adapted for insertion therethrough of a coat hanger hook
whereby to position the collar of a shirt on said hanger
around said segments.

4. The combination of claim 2, said slots being wider
than the thickness of said cams, and said lugs being
spaced from one side of the slots so that said plate is
movable laterally in the slots to move the cams clear
25 of the lugs whereby to permit said springs to move said
segments inwardly to contract said stretcher.

5. The combination of claim 2 and friction brake
means on said lugs and in said slots, engaging said cams
to retain the same in rotated position.

6. The combination of claim 3 and a presser plate op-
erative to press the wings of a collar against one segment,
a presser plate operating member slidably mounted on
said one segment, and coacting camming devices on said
30 tubular member and operating member, respectively, for
sliding said operating member upon rotation of said tubu-
lar member.
